COATING MACHINE

Fay D. Kinney, Southbridge, Mass., assignor to
 United Shoe Machinery Corporation, Paterson,
 N. J., a corporation of New Jersey

Application August 3, 1929, Serial No. 383,231

44 Claims. (Cl. 12—80)

This invention relates to coating machines and is herein illustrated as embodied in a machine for applying cement to bevel edged rubber soles.

The rubber soles which are utilized in the manufacture of tennis shoes, for example, as well as those employed for rubber boots, artics and the like, are made of partly cured rubber stock and are cut out with their edges rather widely and sharply beveled, usually on the side of the sole 5 which is to be secured by cement to the shoe. The application of cement to the attaching surface and the beveled edge of the sole has usually been carried out by hand. It will be understood that rubber soles of this type are naturally 15 limp and very flexible and, furthermore, that the sharply beveled edge of such soles is even more flexible, while the soles usually vary in thickness in different parts, being thinner at the shanks and thicker at the heel parts. It is difficult for a hand operator, therefore, to obtain a 20 very large production combined with a uniform coating and there is, furthermore, a very substantial danger that the outer or tread surface of the soles will be soiled.

Accordingly, one important object of the invention is to provide a coating machine which will satisfactorily coat the attaching surface and the surrounding beveled edge of a piece of work such as a sole and will obtain an increased production at less cost.

To this end one feature of the invention resides in a machine for coating soles having means for feeding the soles in the general direction of their length and having an endless coating applying 30 member which is moved to carry an active portion thereof continuously completely across the faces of the soles in a narrow path transversely thereof, means being provided to apply coating material to the applying member.

Another important feature of the invention resides in construction and arrangement employing a flat-surfaced driven coating brush the axis of which is tilted with respect to a work support beneath the brush whereby one side of 45 the brush will sweep transversely across successive portions of a piece of work presented to the brush, together with means for supplying coating material to the brush. As the work is moved relatively to the brush to cause successive portions thereof to be coated, such movement of the work in the illustrated machine being substantially radially of the brush, the brush sweeps up over the beveled edge of the work and then across its flat surface to apply a uniform coating 50 across its flat surface to apply a uniform coating 55 without danger of smearing the under surface.

In accordance with another feature of the invention, the coating material is supplied to the annular brush of the illustrated machine at a point below the brush, thereby avoiding any difficulties incident to the supplying of coating ma-

terial from a point overhead, and greatly simplifying the machine. When the machine is to be utilized for beveled edged rubber soles, and as herein illustrated, it is provided with a pair of concentric annular brushes rotating in opposite directions and, therefore, arranged to coat the beveled edge of the sole at opposite sides of the sole as well as the intermediate surface of the sole. As illustrated, also, the plane of the work support is tilted with respect to the axes of these 65 brushes so that the active forward portions of the brushes sweep across successive portions of the work, which pieces are then carried forward beneath the elevated rear edges of the brushes without contact therewith.

To assist in increasing the production of the machine the work support of the illustrated machine is in the form of an endless work supporting and conveying belt. There is a tendency for the annular brushes to produce lateral displacement of pieces of work on said belt as the brushes wipe up over the beveled edge of and then sweep across the flat surface of a sole. Accordingly, another feature of the invention resides in improved means for preventing lateral 75 displacement of the work relatively to the belt, such means in the illustrated machine comprising rolls cooperating with the work supporting conveyor and arranged one in front of the line of action of the coating brushes and the other 80 back of the coating brushes as the pieces of work progress from one side to the other thereof. The illustrated roll which is disposed within the brushes is provided with sharp ridges to avoid removing coating material from the already treated 85 pieces of work.

Another feature of the invention resides in a novel arrangement for supporting one end of the conveyor belt which enables the operator readily to adjust the supporting means so as to vary the relative tilting or angular relation of the surface of the supporting belt and the surface of the brushes, to the end that the brushes may be brought into an ideal contacting relation 100 with the soles at the active portion of said brushes and ample space provided between the exit or inactive side of the brushes and the support. In the illustrated arrangement, this adjustment is provided by mounting one of the conveyor rolls upon an adjustable bracket pivoted about the 105 axis of the other roll and, as shown, there is also provided means for adjusting the brushes upon their axes to compensate for wear and to get the desired relation of the tips of the bristles to the work support. Usually, and as illustrated, 110 the adjustable supporting bracket also carries with it the rolls which prevent lateral displacement of the pieces of work and cleaning rolls which together with a separate scraper clean the 115 belt for re-use.

In the illustrated machine, the annular brushes overhang the lateral edges of the conveyor belt and are supplied with cement from a subjacent receptacle by means of supply rolls which dip 5 in the receptacle and convey the cement to the bristles of the brushes, the respective brushes being supplied on opposite sides of said belt. To render easy the care of the machine, the illustrated supply receptacle is made removable and 10 supply rolls which, as illustrated, are journaled in the receptacle, are provided with a detachable driving mechanism so that said rolls and the receptacle may be taken out together.

These and other features of the invention will 15 be better understood from a consideration of the following specification taken in connection with the accompanying drawings in which,

Fig. 1 is a side elevation of the machine with parts broken away and in section;

20 Fig. 2 is an end elevation at the delivery end of the machine; and

Fig. 3 is a plan view of the machine.

Pieces of work, such as rubber soles 10 having outwardly beveled edges around the whole peripheries of the soles are laid upon a work support in the form of an endless belt 12 supported upon rolls 14 and 16. The roll 14 is carried in a machine frame 18 while the roll 16 is mounted in adjustable journal boxes 20 carried at the 25 outer ends of swinging bracket arms 22 and 24. These bracket arms are joined by a plate 26 near their outer ends and are pivoted on a shaft 28 which forms the axis of the roll 14. The work-supporting belt 12 may conveniently be constructed of sheet brass or the like and held under tension by adjustment of the positions of the journal boxes 20 by means of nuts 30 (Figs. 1 and 3).

A coating, such as of cement, is applied to the 40 flat upper surface of each sole 10, which surface is the attaching surface when the sole is assembled in the shoe and also to the sharply beveled edges upon opposite sides of the sole which later are folded over the lower margin of 45 the shoe to produce a rolled edge. The application of cement to the upper surface and to the beveled edge surfaces offers some difficulty because of the different planes in which said surfaces lie but it may be successfully accomplished 50 by means of one or more flat-surfaced, endless, annular brushes 32 and 34 herein shown as of substantial diameter and concentric to each other, said brushes being driven in opposite directions so that the active portions thereof sweep 55 in opposite directions transversely continuously across each sole in a narrow path to apply coating material to the lateral edges and the upper surface of the sole. The relative position of the supporting belt 12 and the lower ends of the brush bristles at one side of the brushes will preferably 60 be such that they almost touch in order that the brushes shall act upon the full width of the beveled edges of the sole as they ride up over said edges and then sweep across the upper surface 65 of the sole. While a single brush may be found satisfactory in treating the upper surface and the beveled edges upon opposite sides of a sole, a pair of brushes will more surely apply the cement to the oppositely beveled edges, and will 70 also be useful in applying successive coats to the flat upper surface of the sole.

These brushes 32 and 34 are supported in a hinged arm 36 which is pivoted in a bracket 38 (Fig. 2) and supported at its other end by means 75 of a bracket 40 to which it is detachably secured

by means of a swinging bolt and a nut 42. When it is desired to lift the brushes for cleaning, the nut 42 is released and the arm 36 swung up until a hook 44 on the arm can be engaged with a latch 46 on the frame of the machine to hold the arm and brushes in raised position.

The lower brush 34 is keyed to an upright shaft 48 (Fig. 2) to which there is splined a mitre gear 50 meshing with a gear 52 upon a shaft 54 journaled in the frame of the machine as well as in said arm 36 and driven from a sprocket 56. It will be noted from Fig. 3 that the shaft 54 has a universal joint 58 to permit tilting movement of the arm 36. The upper and outer brush 32 is keyed to a sleeve forming an extension of another mitre gear 60 (Fig. 2) which is also meshed with the gear 52 and driven in an opposite direction thereby. This mitre gear 60 and its sleeve turn freely about the shaft 48. In order to allow a correct original setting with respect to the work-supporting belt and to permit adjustment to compensate for wear of the brush bristles, provision is made for the vertical adjustment of the two brushes by means of a sleeve 62 threaded externally to engage a portion of 100 the arm 36 and provided with a locking collar 64, said sleeve being rotatably mounted upon an extension of the shaft 48 and held against longitudinal movement thereon by a nut 66.

The driving of the brushes and of the work-supporting belt is effected from an electric motor or the like 70 positioned in the base of the machine. This motor transmits its power through suitable reduction gears 72 to a chain 74 (Fig. 1) transmitting power directly to the shaft 28 105 upon which the belt roll 14 is mounted. Another chain 76 connects the shaft 28 with a hollow shaft 78 to be later described, journaled in a bearing block 79 and the frame of the machine. Upon this shaft there is keyed a double sprocket 80 and the other half of this sprocket transmits power by means of a chain 82 to the sprocket 56 110 at the top of the machine to drive the brushes 32 and 34.

Cement or other coating material is supplied 115 to the brushes 32 and 34 from a receptacle 84 supported on ledges 86 and 88 in a chamber which is practically enclosed by the frame of the machine and by a bottom cover 90. An end plate 92 attached to the receptacle serves as a 120 door for the chamber. This receptacle 84 provides journals for a shaft 94 (Fig. 2) carrying supplying disks 96 and 98 which pick up cement from the receptacle 84 and carry it to delivery disks 100 and 102 which are mounted on a transverse shaft 104 (Fig. 2) carried in loop-shaped brackets 106 and 108 bolted to the inner sides of the frame. The upper portions of the disks 100 and 102 contact respectively with the bristles 125 of the brushes 32 and 34 upon opposite sides of the work supporting belt 12 thus providing for an adequate supply to the oppositely rotating brushes at portions which are approaching the work and without danger of dripping of cement such as might occur in case it were attempted 130 to supply cement from overhead. In order to permit removal of the receptacle, the shaft 94 is adapted to be releasably connected to the hollow shaft 78 already mentioned by means of a sliding plunger 110 carried within the hollow 135 shaft 78 and having a tongue 112 in its inner end to coat with a suitable slot in the end of the shaft 94. This plunger 110 is spring-pressed in a direction to connect the shafts 78 and 94 and is splined to the hollow shaft 78. The 140 145 shaft 78 and having a tongue 112 in its inner end to coat with a suitable slot in the end of the shaft 94. This plunger 110 is spring-pressed in a direction to connect the shafts 78 and 94 and is splined to the hollow shaft 78. The 150

plunger 110 is provided with an operating handle 114 outside the frame of the machine. This handle 114 is rotatably mounted on the plunger 110 and is provided with an inwardly 5 projecting lug 116 adapted to engage a corresponding slot in the enlarged end 118 of the hollow shaft 78. When the handle 114 is pulled out to disengage the driving connection between the shafts 78 and 94, it may be given a partial 10 rotation to cause the lug 116 to rest on the enlarged end 118 of the hollow shaft 78 to hold the plunger 110 against the tension of its spring. When it is desired to re-engage the parts after the cement receptacle has been replaced, 15 then the handle 114 is again turned so that its tongue 116 will drop into the slot of the enlarged end 118 and allow the tongue 112 on the plunger 110 to re-engage the shaft 94. At the other end of the shaft 94 there is provided a locating 20 device in the form of a removable stud 120 which passes through the frame of the machine and enters a recess in the end of the shaft 94. It will be noted that the shaft 104 carrying the upper disks is connected to the driven shaft 78 25 carrying the lower disks by means of intermeshing gears 122 and 124. As a consequence the pairs of disks 96-98 and 100-102 are driven in opposite directions and the upper portions of the peripheries of the upper disks 100-102 move 30 in such directions that they oppose the directions of movement of the bristles of the coating brushes so that the cement is wiped onto said brushes and an adequate supply therefor insured. 35 Because of the lateral movement of the brushes with respect to the soles upon the belt 12 there is some tendency to the lateral displacement of said soles. This is counteracted, however, by means of rolls 130 and 132 (Fig. 1) which contact with the upper surface of the successive soles 10 just in 40 front of or outside and just back of or inside the line of action of the brushes to prevent lateral displacement and to insure the satisfactory progressive movement of the soles with the supporting belt 12, said rolls co-acting with the belt to that end. The roll 130 is nurled and is mounted 45 for free rotation by means of studs 134 in a swinging arm 136 extending from side to side of the belt and pivoted at its ends upon brackets 138 and 140 attached to the long bracket arms 22 and 24 respectively. These brackets 138 and 140 also 50 provide for the support of backing rolls 142 and 144 underlying the belt 12 to prevent downward deflection of the belt and make the action of the rolls 130 and 132 more positive. Adjustable studs 55 146 upon the respective brackets 138 and 140 engage the sides of the swinging arm 136 to support the roll 130 in a position slightly elevated above the belt 12 so that the advancing beveled edge of a sole 10 will not be curled up upon engagement with said roll 130 but will progress far enough under the bite of the roll 130 to insure the coaction of said roll with the belt in advancing the sole to the action of the brushes, it being understood that the weight of the roll 130 and associated parts is depended upon to hold said roll in engagement with successive soles. It is noted that the roll 132 is made up of series of disk-like members (Fig. 3) to avoid removing 60 cement from the already coated sole, said members being journaled in a curved extension 146 (Fig. 3) of a transverse arm which has depending terminal portions 148 (Fig. 1) which are pivoted on upwardly extending lugs integral with the brackets 106 and 108 which are bolted to the inner 65 sides of the frame. 70

When pieces of work have been coated, they pass under the inactive portions of the brushes 32 and 34, because of the relative inclination of the belt 12 to the plane of the bottoms of said brushes, and then they are removed from the belt 12 by 75 means of a work stripper 150 carried on pivoted arms 152 which may be adjustably mounted in brackets 154 secured to the frame of the machine. Spring pressed abutment screws 156 are provided to engage the opposite sides of the upper end of the arms 152 and said arms are held in the brackets 154 by means of removable studs 158. 80

The surface of the belt 12 is bound to become coated with cement to a substantial extent, partly because of the fact that the soles do not completely cover the belt and partly because there may be spaces between the successive soles. At any rate, a series of scraper blades 160 separated at their ends by spacing blocks are bolted on a swinging carrier 162 supported by detachable studs 164. The blades 160 are thus held by gravity in engagement with the belt 12 where it is passing over the roll 14. A handle 166 is provided for the carrier 162 so that said carrier may be lifted up when it is desired to remove the receptacle 85 84, in order to avoid interference between the disks 96 and 98 and said scrapers 160. The cement which is taken off the belt by the scrapers 160 passes down between the respective spaced scraper blades directly into the receptacle 84. 90 95 100

In order to perfect the cleaning of the outer surface of the belt 12 before it comes back into position for the reception of additional pieces of work a series of cleaning rolls 170 (Fig. 1) are provided which may be covered with friction tape 110 or the like to provide a tacky surface to which particles of cement will adhere. These rolls contact with the idle run of the belt and are journaled in a swinging carrier 172 pivoted upon the arms 22 and 24 and adapted to be held in fixed relation 115 thereto by removable studs 174 engaging the upper ends of upright arms 176 on said carrier. The carrier comprises side arms connected by an end piece 178 and a web 180 and each of the rolls 170 is journaled in a box slidable vertically in the 120 side arms of the carrier and spring-pressed to hold said rolls in engagement with the outer surface of the belt 12. The two right-hand rolls, as shown in Fig. 1, cooperate with backing rolls 182 supported in brackets 184 attached to the cross 125 strip 26, while the left-hand roll 170 presses against the belt at a point where it is supported by the roll 16. 130

To take care of wear of the brush bristles and to insure such an angular relation between the belt 12 and the brushes that there will be ample room for an exit of the pieces of work without disturbance by the brushes, the bracket arms 22 and 24 with all the parts carried thereby may be moved up and down by means of a screw connection to a sliding stud 190 mounted in an auxiliary casing 192 and pivotally connected at its upper end to said bracket arms 22 and 24. A hand wheel 194 is connected by a worm to the nut 196 by which the position of the rod 190 is adjusted, thus facilitating an accurate positioning of the belt with respect to the plane of the flat-surfaced brushes. 135 140

In the use of the machine, after the various 145 adjustments have been effected to raise or lower the brushes as desired and to vary the inclination of the belt 12, and supposing that coating material has been supplied to the receptacle 84, the electric motor may be set in motion and successive soles laid upon the belt 12 at its left-hand 150

- end as seen in Fig. 1. The soles will be carried along the belt beneath the roll 130 and the brushes 32 and 34 and the roll 132, which rolls prevent lateral displacement of the soles as they are coated by the brushes and insure continual progress of the soles with the belt. The soles will be removed from the belt by the work stripper 150 and in accordance with the usual factory practice, will be transferred to a drying conveyor.
- 10 Having thus described my invention, what I claim as new and desire to secure by Letters Patent of the United States is:
1. In a coating machine, an endless work-supporting belt, a power-driven flat-surfaced coating brush positioned over said belt having its axis tilted with respect to said belt and constructed and arranged to sweep one side of the brush across successive portions of a piece of work upon the belt, and means for supplying coating material to said flat-surfaced brush for application to the work.
  - 15 2. In a coating machine, a work-support, a driven flat-surfaced coating brush, the plane of said work-support being tilted with respect to the axis of said brush so that one side of the brush will sweep across successive portions of the surface of the piece of work presented to the brush to permit passage of the piece of work beneath the other side of the brush without contact therewith, and means for supplying coating material to said brush for application to the work.
  - 20 3. In a coating machine, a work-support, a driven annular coating brush, the plane of said work-support being tilted with respect to the axis of said brush so that one side of the brush will sweep across successive portions of the surface of a piece of work presented to the brush, and means disposed below the work support for supplying coating material to said brush for application to the work.
  - 25 4. In a coating machine, a movable work-supporting conveyor, a driven annular coating brush disposed above the conveyor and arranged to sweep across the conveyor and a piece of work thereon, and means disposed below said conveyor for feeding coating material to said brush.
  - 30 5. In a coating machine, a work-supporting conveyor, an annular brush disposed above said conveyor and driven to sweep across the conveyor and a piece of work supported thereon, said brush overhanging one edge of the conveyor, and means disposed laterally of the conveyor and beneath the brush for supplying coating material to the brush.
  - 35 6. In a coating machine, a work-support, a pair of brushes rotated in opposite directions and having their axes tilted with respect to said work support to bring one edge of each brush into active contact with the work whereby the active edges of the brushes are arranged to sweep across pieces of work on the support in opposite directions to the end that pieces of work having oppositely beveled edges may be coated on one surface and said edges.
  - 40 7. In a coating machine, a work-support, and a pair of concentrically arranged annular brushes driven in opposite directions and arranged to sweep across a piece of work on the support.
  - 45 8. In a coating machine, a pair of concentrically arranged annular brushes driven in opposite directions and arranged to sweep across a piece of work, and means for feeding a piece of work substantially radially of the brushes.
  - 50 9. In a coating machine, a work-support, a pair of concentrically arranged annular brushes driven in opposite directions and arranged to sweep across a piece of work on the support, and means disposed below the brushes for supplying cement to each of said annular brushes.
  - 55 10. In a coating machine, a work-support, a pair of concentric annular brushes driven in opposite directions arranged to sweep across a piece of work on the support and to overhang the sides of the support, and means disposed below the support for supplying cement to the overhanging portion of each of said annular brushes.
  - 60 11. In a coating machine, a work-support, a pair of concentrically arranged annular brushes driven in opposite directions arranged to sweep across a piece of work on the support and to overhang the sides of the support, and means disposed laterally of the support to supply coating material to each brush as it approaches the work.
  - 65 12. In a coating machine, a conveyor belt, oppositely driven annular brushes arranged to sweep in opposite directions across a piece of work on the conveyor belt and to overhang said belt, and means one on one side of the belt and the other on the other side and disposed below the belt to supply coating material to said brushes at portions of the brushes which are approaching the work.
  - 70 13. In a coating machine, a work-support, a pair of concentrically arranged annular brushes driven in opposite directions arranged to sweep across a piece of work on the support, and means for supporting and driving said brushes constructed and arranged to allow the brushes to be tilted away from the work support to give access to the brushes.
  - 75 14. In a coating machine, a conveyor belt, a pivoted support above said belt, an annular brush rotatably mounted in said pivoted support, driving means for said brush constructed and arranged to allow tilting movement of said brush support with said brush, and means for supplying coating material to the bristles of the brush disposed laterally of the conveyor and below the brush.
  - 80 15. In a coating machine, a driven conveyor, a coating brush arranged to sweep across the surface of the conveyor, and separate members disposed the one in front of and the other in back of the line of action of said brush to cooperate with the work upon the conveyor to prevent lateral displacement of a piece of work carried under the brush by the conveyor.
  - 85 16. In a coating machine, a driven conveyor, an annular brush rotatable about an axis tilted with respect to the surface of the conveyor and arranged to sweep across a piece of work on the conveyor, and means for preventing lateral displacement of the piece of work on the conveyor under the action of said brush, said tilted position of the axis of the brush permitting passage of the pieces of work beneath the other side of the brush without contact therewith.
  - 90 17. In a coating machine, an endless work-supporting belt, an annular brush rotatable about an axis tilted with respect to the surface of the belt, and arranged so that one side of the brush will sweep across successive portions of the surface of a piece of work presented to the brush by the belt, and a roller movably mounted just outside the periphery of the brush to bear against the surface of a piece of work carried by the belt thereby to assist in the feeding movement imparted to the work by the belt and to prevent
  - 95 18. In a coating machine, a work-support, a pair of concentrically arranged annular brushes driven in opposite directions arranged to sweep across a piece of work on the support and to overhang the sides of the support, and means disposed below the support for supplying cement to the overhanging portion of each of said annular brushes.

- lateral displacement of the work under the action of the brush.
18. In a coating machine, an endless work-supporting belt, an annular brush rotatable about an axis tilted with respect to the surface of the belt and arranged so that one side of the brush will sweep across successive portions of the surface of a piece of work presented to the brush by the belt, and means for preventing lateral displacement of successive pieces of work under the action of the brush comprising rolls disposed just outside and inside the periphery of the active edge of the brush, said rolls bearing against the pieces of work on the belt.
19. In a coating machine, an endless work-supporting belt, an annular brush rotatable about an axis tilted with respect to the surface of the belt, and arranged so that one side of the brush will sweep across successive portions of the surface of a piece of work presented to the brush by the belt, and means for preventing lateral displacement by the brush of successive pieces of work presented by the belt, said means comprising backing means to support the belt at the section lying beneath the active portion of the brush together with a nurled roll just outside the periphery thereof pressed by gravity against the surface of each piece of work presented to the brush and another roll just inside the periphery of the brush made of a series of sharp edged members pressed lightly against the surface of each piece of work.
20. In a coating machine for soles having beveled edges, an endless work-supporting belt, a treating brush rotatable above the belt, an un-driven roll yieldably pressed against successive pieces of work brought forward by the belt to assist in feeding the work, and means for normally supporting said roll in a position spaced slightly above the surface of the belt to allow the advancing beveled edge of a sole to progress under the lowest point of the roll before the roll comes into contact with a sole, said means permitting the roll to be raised by contact with the sole.
21. In a coating machine, a driven work-supporting belt, an annular brush rotatable about an axis tilted with respect to the surface of the belt so as to contact with pieces of work on the belt at one side only of the brush, and means disposed inside and outside of said annular brush to cooperate with the belt and pieces of work supported thereon, to prevent lateral displacement of said pieces of work under the action of the brush.
22. In a coating machine, a driven work-supporting belt, an annular brush rotatable about an axis tilted with respect to the surface of the belt so as to contact with pieces of work on the belt at one side only of the brush, means disposed inside and outside of said annular brush to cooperate with the belt and pieces of work supported thereon to prevent lateral displacement of said pieces of work under the action of the brush, and means for simultaneously adjusting said belt and said displacement means so that the angular relation of the belt to the brush may be varied without altering the relation of the displacement preventing means to the belt.
23. In a coating machine, a work-supporting belt, a coating brush arranged to sweep across the surface of the belt to apply coating material to successive portions of pieces of work carried by the belt, a roll resting against the surface of pieces of work just in front of the line of action of said brush to assist the belt in feeding the work, and a sharp edged member resting against pieces of work just back of the line of action of said coating brush to prevent lateral displacement of the work by the brush without removing any substantial quantity of coating material.
24. In a cementing machine, a driven work-supporting belt, a brush disposed above said belt arranged to sweep transversely across the belt to coat successive portions of an article carried thereon, and tacky cleaning rolls contacting with the idle run of the belt for removing coating material which has adhered to the belt.
25. In a cementing machine, a driven work-supporting belt, a brush disposed above said belt arranged to coat successive portions of an article carried thereon, scrapers resting against the belt and arranged to remove the bulk of the cement which has been deposited upon the belt, and tacky cleaning rolls for removing portions of cement which were not removed by the scrapers.
26. In a coating machine, a driven work-supporting belt, a brush disposed above said belt arranged to coat successive portions of an article carried thereon, a backing member behind said belt, and a tacky cleaning roll movably mounted and spring-pressed into contact with the belt opposite said backing member to pick up and remove coating material remaining on the belt.
27. In a coating machine, a driven work-supporting belt, a brush disposed above said belt arranged to coat successive portions of an article carried thereon, backing means cooperating with the inner surface of said belt, and a cleaning roll spring-pressed into contact with the outer surface of the belt in opposition to said backing means thereby to remove coating material which remains upon the belt.
28. In a coating machine, an endless work-supporting belt, rolls for supporting said belt at its opposite ends, a coating brush with the tips of its bristles in a plane, means for supplying coating material to the bristles of said brush for transfer to the work, the brush being disposed above the upper run of the belt and arranged to sweep across said belt to coat an article supported thereon, and an adjustable bracket for supporting one of said belt rolls whereby the angular relation of the belt to the plane of the coating brush may be varied to provide a suitable passage for the work beneath one side of the brush without disturbing the relation of the brush to the supply means.
29. In a coating machine, an endless work-supporting belt, rolls for supporting said belt at its opposite ends, a flat-surfaced coating brush disposed above the upper run of the belt and arranged to sweep across said belt to coat an article supported thereon, means cooperating with said belt to prevent lateral displacement of the pieces of work by the action of the brush, and an adjustably supporting bracket for said displacement-preventing means and one of the belt rolls whereby the belt and said means may be simultaneously adjusted thereby to vary the angle between the belt and the surface of the brush.
30. In a coating machine, an endless work-supporting belt, rolls for supporting said belt at its opposite ends, a flat-surfaced coating brush disposed above the upper run of the belt and arranged to sweep across said belt to coat an article supported thereon, a cleaning roll associated with the under run of the belt, and an adjustable bracket for supporting said cleaning roll and one of said belt rolls whereby the belt and the cleaning roll may be simultaneously adjusted there-

by to vary the angle between the belt and the surface of the brush.

31. In a coating machine, an endless work-supporting belt, rolls for supporting said belt at its opposite ends, a flat-surfaced coating brush disposed above the upper run of the belt and arranged to sweep across said belt to coat an article supported thereon, means for supplying coating material to the under side of said brush, a bracket pivoted for movement about the axis of one of said belt rolls arranged to carry the other belt roll, and means for adjusting the position of said bracket thereby to vary the angle between the belt and the surface of the brush.

15 32. In a coating machine, an endless work-supporting belt, rolls for supporting said belt at its opposite ends, a coating brush disposed above the upper run of the belt and arranged to sweep across said belt to coat an article supported thereon, a backing roll disposed beneath the belt adjacent to the point of contact between the brush and a piece of work supported on the belt, and means for adjustably supporting said backing roll.

25 33. In a coating machine, an endless work-supporting belt, rolls for supporting said belt at its opposite ends, a flat-surfaced coating brush disposed above the upper run of the belt and arranged to sweep across said belt to coat an article supported thereon, a backing roll disposed beneath the belt adjacent to the point of contact between the brush and the work, and an adjustable bracket for supporting said backing roll and one of said supporting rolls to provide for simultaneous adjustment of the belt and its backing roll thereby to

30 35 vary the angle between the belt and the surface of the brush.

34. In a coating machine, an endless work-supporting belt, rolls for supporting said belt at its opposite ends, a flat-surfaced coating brush disposed above the upper run of the belt and arranged to sweep across said belt to coat an article supported thereon, backing rolls disposed beneath said belt at opposite sides of the line of contact between the brush and the work supported thereon, and means for simultaneously adjusting said backing rolls and said belt, thereby to vary the angle between the belt and the surface of the brush.

35. In a coating machine, a driven work-supporting belt, an annular coating brush disposed above said belt and arranged to sweep across the surface of the belt, said brush over hanging said belt at one side, a receptacle disposed below said belt, and a roller for picking up coating material from the receptacle and delivering it to the brush at a point laterally of the belt.

40 45 50 55 60 65 36. In a coating machine, a driven work-supporting belt, a pair of concentric annular brushes supported above and overhanging said belt arranged so that one side of each brush sweeps across successive portions of an article carried on the belt, a receptacle below the belt, and driven coating rollers for transferring coating material from the receptacle to said brushes at points outside of said belt.

37. In a coating machine, a driven work-supporting belt, a pair of concentric annular brushes supported above and overhanging said belt arranged so that one side of each brush sweeps across successive portions of an article carried on the belt, a receptacle below the belt, and driven coating rollers for transferring coating material from the receptacle to said brushes at points outside of said belt, said transferring rollers being driven in such a direction that contacting adja-

cent surfaces of the transferring rollers and the brushes are moving in opposite directions.

38. In a coating machine, a work-support, an annular brush rotatable above said work-support to sweep across successive portions of a piece of work thereon, a removable receptacle beneath the work-support, a supply roll journaled in the receptacle, a delivery roll journaled in the frame of the machine and arranged to transfer coating material from said supply roll to said annular brush, and means for driving said supply roll constructed and arranged to permit removal of the receptacle with the supply roll.

80 85 90 95 100 105 110 115 120 125 130 135 140 145 150 39. In a coating machine, an endless work-supporting belt, concentric annular brushes disposed above said belt driven to sweep in opposite directions across a beveled edge sole carried by the belt, delivery rolls disposed laterally of the conveyor belt and cooperating with said brushes respectively, a removable receptacle for coating material disposed beneath the conveyor belt, driven supply rolls journaled in said receptacle to supply material to said delivery rolls, and means for driving said brushes and rolls in such directions that the contacting surfaces between the supply rolls and the delivery rolls are moving in the same direction while the contacting surfaces between the transferring rolls and the brushes are moving in opposite directions.

100 105 110 115 120 125 130 135 140 145 150 40. In a machine for coating soles, means for feeding soles in the general direction of their length, an endless coating member having an active portion movable continuously in a narrow path transversely of the soles and completely across the faces of the soles, means beneath the said coating member for supplying the coating material thereto, and means for moving said member to carry its active portion continuously in one direction transversely of the direction of feed.

41. In a machine for cementing soles, means for feeding soles in the general direction of their length, flexible applying means movable transversely of the soles completely across the faces of the soles to coat the whole surfaces thereof, means for supplying cement to said applying means, and means for preventing lateral displacement of the soles by the action of said applying means.

120 125 130 135 140 145 150 42. In a cement-applying machine, means for feeding soles in the general direction of their length, oppositely moving cement-applying means adapted to be moved transversely of the soles to coat the whole width of the surfaces thereof, means for supplying cement to said applying means, and means for preventing lateral displacement of the soles.

43. In a machine for cementing soles with beveled edges, means for feeding soles through the machine in the direction of their longitudinal axes, adjacent rows of flexible bristles moving in opposite directions for applying cement to the opposite beveled edges and one surface of a sole, means for supplying cement to said rows of bristles, and means for preventing lateral displacement of the sole.

135 140 145 150 44. In a machine for cementing soles with beveled edges, means including a conveyor for feeding soles through the machine in the direction of their longitudinal axes, rows of flexible bristles moving continuously in opposite directions for applying cement to the beveled edges and one surface of a sole, and means for supplying cement to said rows of bristles.
